TABLE

Florian E. Gierlich, Wichita, Kans., assignor to
Engineering Service, Inc., Wichita, Kans.

Application May 17, 1949, Serial No. 2,707

Term of patent 14 years

(Cl. D33—14)

To all whom it may concern:

Be it known that I, Florian E. Gierlich, a citizen of the United States, residing at Wichita, in the county of Sedgwick and State of Kansas, have invented a new, original, and ornamental Design for a Table, of which the following is a specification, reference being had to the accompanying drawings, forming a part thereof.

Figure 1 is a perspective view of a table, showing my new design, the top of the table being illustrated in a vertical position to show its under side, and the standard of the table being shortened;

Figure 2 is a perspective view showing the table top adjusted to a slight angular position with respect to the horizontal, and the standard being lengthened;

Figure 3 is a perspective view showing the table top adjusted to a horizontal position and with the standard adjusted to the position of Figure 1.

The characteristic feature of my design for the table resides in the specific configuration of the spider member at the top of the pedestal, as particularly shown in Figure 1.

I claim:

The ornamental design for a table, as shown and described.

FLORIAN E. GIERLICH.
